(57) CLAIM

The ornamental design for the sport bag, as shown.

DESCRIPTION

FIG. 1 is a front perspective view of the sport bag, showing my new design.

FIG. 2 is a front elevational view thereof.

FIG. 3 is a rear elevational view thereof.

FIG. 4 is a right-side elevational view thereof.

FIG. 5 is a left-side elevational view thereof.

FIG. 6 is a top view thereof; and,

FIG. 7 is a bottom view thereof.

The thick broken lines showing paddles in FIG. 1 are for showing environment only and form no part of the invention. The remaining thick broken lines depict portions of the sport bag that form no part of the invention. The thin broken lines show stitch lines that do not form part of the invention.
